UNITED STATES PATENT OFFICE.

WILLIAM E. HALE, OF PHILADELPHIA, PENNSYLVANIA, ASSIGNOR TO R. H. BEAUMONT COMPANY, OF PHILADELPHIA, PENNSYLVANIA, A CORPORATION OF PENNSYLVANIA.

MEANS FOR OPERATING OVERHEAD VALVES OF COALING APPARATUS.

1,272,037.

Specification of Letters Patent.

Patented July 9, 1918.

Application filed December 5, 1917. Serial No. 205,520.

To all whom it may concern:

Be it known that I, WILLIAM E. HALE, a citizen of the United States, residing in Philadelphia, Pennsylvania, have invented 5 certain Improvements in Means for Operating Overhead Valves of Coaling Apparatus, of which the following is a specification.

One object of my invention is to improve the means for operating the bunker gates 10 of an overhead storage system used in connection with lorries for discharging coal or other fuel from the bunker to the hoppers of stokers connected to boilers, or other furnaces.

15 A further object of the invention is to prevent the duplication of the operating mechanism of the several gates and to provide a single device carried by the traveling lorry, which device is in operative position 20 when the lorry is under a given bunker discharge opening.

In the accompanying drawings:—

Figure 1, is a side view of a coal handling apparatus showing the bunker in section 25 and the gate operating mechanism on the lorry clear of the gate connections;

Fig. 2, is a front elevation of the device illustrated in Fig. 1;

Fig. 3, is a perspective view of one of the 30 gates and its connection;

Fig. 4, is a perspective view of the mechanism carried by the lorry;

Fig. 5, is a diagrammatic view, showing the hook in engagement with the gate bar, 35 the gate being in the closed position;

Fig. 6, is a view, showing the hook in engagement with the bar and the gate in the extreme open position; and

Fig. 7, is a side view of the hook.

40 Referring to the drawings, 1, 1 are the overhead beams supported in any suitable manner, and on these beams are rails 2. 3 is the lorry structure having axles 4 on which are mounted wheels 5 which travel on the 45 rails 2. The lorry structure consists of a frame 6 made of angle irons, or other metal shapes and arranged to support the hopper 7 having one or more chutes 8 arranged to discharge, in the present instance, into the 50 magazine of a boiler furnace. It will be understood that the shape of the lorry and the particular structural work of the frame may be modified without departing from the essential features of the invention.

The invention relates particularly to the 55 means on the lorry for operating the gates of the bunker. 9 is the bunker, supported on any suitable structure, and 11 is a casing forming one of the bunker discharge openings. The casing has a curved end and 60 adapted to close the opening is a curved gate 12 which is pivoted at 13 to the casing and has arms 14 to which are attached the bars 15, one on each side of the gate in the present instance. The bars are supported 65 on a bar 16 carried by a fixed hanger 17 in close proximity to the gate.

Two rods 10 and 18 connect the outer ends of the bars 15 and these rods are in position to be engaged by a hook 19 on a shaft 20 70 adapted to a bearing 21 mounted on the lorry frame and on the shaft 20 is a bevel pinion 22, which meshes with a bevel pinion 23 on a vertical shaft 24 adapted to bearings 25 on the lorry frame and having at its 75 lower end an operating handle 26. On turning this handle, the vertical shaft 24 and the horizontal shaft 20 are turned and the hook moves from the position illustrated in Fig. 1 to a position illustrated in Fig. 6, 80 opening the gate to its full extent.

It will be noticed that when the hook is in the position illustrated in Fig. 1, it is clear of the gate rods 10 and 18, so that the lorry frame can be moved on its rails with- 85 out the hook coming in contact with any of the operating mechanism, but when it is desired to open a given gate, then the hook is moved in the position shown in Fig. 5, in engagement with the rod 18, the gate being 90 still closed. On moving the hook to the position shown in Fig. 6 it engages the rod 18 and moves the gate 12 to the open position and the coal, or other material, is allowed to flow from the bunker into the lorry, and by reversing the movement the hook 19 presses upon the rod 10 and forces the gate into the closed position. Thus it will be seen that a single operating device carried by a lorry 95 structure can actuate the several gates of a bunker, so that all suspending devices at the several gates are dispensed with. This is particularly advantageous in boiler rooms where the space is cramped to a certain degree, and where the gate operating devices 100 are liable to interfere with other mechanism.

The hook 19 is made as shown in Figs. 4,

5 and 6, having a main hook 27 and a heel 28 forming between them a notch to receive the bar 18; the heel 28 prevents the rod and its bar from dropping out of the hook when in 5 the position illustrated in Fig. 6. The back of the hook is rounded as shown so that it will engage the rod 10 when closing the gate.

While I have described my invention in 10 connection with bunkers and lorries handling coal or other fuel, the invention can be used for handling any granular material in bulk.

I claim:—

- 15 1. The combination of a bunker having a discharge opening; a pivoted gate arranged to open and close said opening; two bars, one at each side of the gate and connected thereto; a cross rod connecting the ends of the two bars; a traveling lorry; a shaft; a hook on the shaft arranged to engage the rod and to move the gate to the open position; a vertical operating shaft having its bearings on the lorry structure; gearing between the vertical shaft and the hook shaft; and means for manually operating the vertical shaft so that on turning the shaft the hook will engage the rod and will open the gate.
- 20 2. The combination of a bunker having a discharge opening; a gate arranged to close said opening; a bar connected to the gate; two rods attached to the outer end of the bar; a lorry; a shaft on the lorry; and

means for turning the shaft, said shaft having a hook arranged to enter the space between the two rods and operate the gates through the bar.

3. The combination of a bunker having a discharge opening; a gate arranged to close 40 said opening; two bars connected to the gate; means for supporting the bars; two rods connecting the outer ends of the bars; a lorry; a shaft on the lorry; and means for turning the shaft, said shaft having a hook 45 arranged to enter the space between the two rods on the bars and operate the gate through said bars.

4. The combination of a bunker having a discharge opening; a pivoted gate arranged 50 to close said discharge opening; a bar pivoted to the gate; a fixed support for the bar, said bar having a rod at its outer end; a traveling lorry arranged to move horizontally under the bunker; a shaft on the lorry 55 structure; an arm on said shaft having a hook; a heel back of the hook and arranged to engage the rod on the end of the gate bar; a beveled gear wheel on said shaft; a vertical shaft on the lorry structure having a beveled gear wheel meshing with the bevel gear wheel on the hook shaft, said vertical shaft extending to the lower portion of the lorry structure and having a handle by 60 which it can be turned.

In witness whereof I affix my signature.

WILLIAM E. HALE.
